UNITED STATES PATENT OFFICE

GUNNAR D. GUSTAFSON, OF CHICAGO, ILLINOIS

WATCH TIMER

Application filed February 1, 1932. Serial No. 590,190.

This invention relates to an improved method of obtaining an indication of the relative time intervals of two time pieces.

The main object of my invention is to provide an indicator or recorder which indicates rapidly the time interval of a watch as compared with a master or standard; and further to provide an electrically operated pointer which by its movement shows unison or lack of unison in time pieces; to provide an electrically operated mechanical movement controlled by sound or tick from a time piece; to provide microphones or the like, excited by time pieces, to control the mechanical movement of the time indicator; to provide an indicator arranged to show the resultant of two motions in time relation; and to provide a stylus on the indicating needle which makes a record on a chronograph.

An illustrative embodiment of my invention is shown in the accompanying drawing in which:

Figure 1 is a diagrammatic drawing of the complete apparatus.

For illustrative purposes a master time piece 1 is shown adjacent the microphone 2. In circuit with the microphone 2 is an electromagnet 3 and a battery 4, connected to form a closed circuit by leads 5, 6 and 7. An armature 8 placed in the field of the electromagnet swings on a pivot 9, and is connected by pivot 10 to a link 11, which slides in a loosely fitting guide 12. The link 11 is pivoted at 13 to one leg of a bifurcated needle or pointer 15. At the upper end of the needle is a stylus 16 which bears on a roll of paper 17, driven by a clock movement in the case 18. The other leg 19 of the bifurcated needle 15 is connected to the armature 20 by a link 21.

A second electromagnet 22 is in circuit with a battery 23, and a microphone 24, which is in working range of the watch 25. On the needle 15 is fastened a lug 26 positioned to engage a one-way gravity latch 27, which is pivoted to a bell crank 28. The bell crank 28 is arranged to close an electric circuit comprising a terminal 29, a source of E. M. F. 30, a lead 31, an incandescent lamp 32, and a lead 33, completing the circuit to the bell crank.

The gravity latch 27 is located to coact with

a lug 26 when the needle 15 is moved to the left of its zero position, and the circuit through the lamp 32 is only closed when the lug 26 is traveling upwards.

In operation the sound waves from the tick of the time piece control the pulsations of current which flow from the battery through the microphone and the electromagnet. Assume that the master time piece is in sound control of its microphone, putting only one armature in motion. Then the stylus on the needle will describe an arc substantially at right angles to the motion of the link. The motion is that of a bell crank.

In case the watch to be tested is placed in working range of its microphone, with the master removed from control, then the stylus will describe the same arc at right angles to direction of motion.

The most important motion is that which is obtained when both the master and the watch under test are in unison and in phase. Then the needle will travel straight up and down. In actual practice the master clock through its time control is adjustable until the two time pieces are in exact phase, which is indicated when the needle travels straight up and down, with no side motion. The maximum side motion is produced when the time pieces are out of phase.

In all phase relations the resultant described will vary from an ellipse to a circle. One of the main features of my time arrangement is that the direction of rotation of the stylus, right-handed or left-handed, depends on whether the watch under test is faster or slower than the master. A visible indication of the direction of rotation is obtained by providing the needle with a lug which has a free movement, up and down, when the time pieces are in phase, and the lug makes contact with the one-way gravity latch when the needle is traveling to the left of its zero position. When the direction of rotation is right-handed or clock-wise, then the latch, through the bell crank, closes the electric circuit, lighting a lamp. Thus a lamp arranged as here described, indicates which of the two time pieces is fast. If the lamp does not light, the operator knows the

stylus is rotating left-handed. The phase relations are continuously changing, except when the master and the watch under test are in unison.

5 A complete graphical record of the relative time intervals is recorded on the moving paper on the chronograph by the stylus. The graphic record is capable of an analysis similar to that from an indicator card taken
10 from an engine.

Although but one specific embodiment of this invention has been herein shown and described, it will be understood that certain details of the construction shown may be altered or omitted without departing from the spirit of this invention as defined by the following claims.

I claim:

1. A device for detecting the difference
20 in rates of vibration of separate sounds consisting of independent sound responsive elements, a lever connected for vibration with each of said sound responsive elements, and a recording means connected with one of
25

said levers for movement in one direction, and with another of said levers for movement in another direction.

2. A means for recording the difference in rates of vibration from separate sources of sound comprising a recording member having two pivotal supports, each of said supports being movable, sound responsive means for imparting movement to one of said supports and separate sound responsive means for imparting movement to the other of said supports.

3. Recording means of the class described, comprising a vibratable needle, a pair of eccentrically spaced pivotal supports for said needle, each of said supports being movably mounted, electro-magnetic means for vibrating each of said supports, a pair of microphones, and circuit connections for said microphones whereby each microphone may control the operation of one of the electro-magnetic means for vibrating a pivotal support for the needle.

GUNNAR D. GUSTAFSON.
